[57] CLAIM

The ornamental design for a liquid-crystal time display apparatus, as substantially shown and described.

DESCRIPTION

FIG. 1 is a front elevational view of a liquid-crystal time display apparatus showing my new design;

FIG. 2 is a left side elevational view thereof and the right side view is identical;

FIG. 3 is a top plan view thereof and the bottom plan view is identical;

FIG. 4 is a rear elevational view thereof; and

FIG. 5 is a front elevational view thereof in the functional or active state.

FIG. 1

FIG. 2

FIG. 3

FIG. 4

FIG. 5
